UNITED STATES PATENT OFFICE

ROBERT W. THOMAS, OF LANCASTER, OHIO, ASSIGNOR TO GENERAL GLASS CORPORATION, OF LANCASTER, OHIO, A CORPORATION OF INDIANA

DESIGN FOR A MUG OR SIMILAR ARTICLE

Application filed March 24, 1932. Serial No. 43,280. Term of patent 3½ years.

To all whom it may concern:

Be it known that I, ROBERT W. THOMAS, a citizen of the United States of America, residing at Lancaster, in the county of Fairfield and State of Ohio, have invented a new, original, and ornamental Design for a Mug or Similar Article, of which the following is a specification, reference being had to the accompanying drawing, forming part thereof.

Fig. 1 and Fig. 2 are elevations of a mug or similar article showing my new design, the two figures being taken from slightly different viewpoints.

Fig. 3 is a bottom plan of a mug or similar article as shown in Figures 1 and 2.

I claim:

The ornamental design for a mug or similar article, as shown.

ROBERT W. THOMAS.
